Primary Examiner — Dana K Weiland*Assistant Examiner* — Mary Claire Ramirez(74) *Attorney, Agent, or Firm* — Muncy, Geissler, Olds & Lowe, P.C.(57) **CLAIM**

The ornamental design for a driving unit for a camera lens, as shown and described.

DESCRIPTION

FIG. 1 is a top perspective view of a driving unit for a camera lens showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is another perspective view thereof.

The broken lines shown in the drawings depict portions of the driving unit for a camera lens that form no part of the claimed design.
